TESTING APPARATUS

John D. Hird, Washington, D. C.

Application June 30, 1934, Serial No. 733,294

5 Claims. (Cl. 88—14)

This invention is directed to an improvement in a testing apparatus wherein provision is made for the use and control of reflected light to enable such reflected light to be sent directly and longitudinally of containers for the material to be tested, with adjustable provisions for viewing the containers and material therein in the line of the reflected light.

The primary object of the present invention is the provision of a simple testing apparatus involving a case for the removable reception of containers for the material to be tested, together with a mirror or light reflecting surface arranged below the containers and capable of angular adjustment to cause light rays to be reflected directly and longitudinally of the containers, together with an upper reflecting element which may likewise be adjusted to permit the containers to be visible in the line of their axes, so that the entire body of material being tested is illuminated directly by the reflected light and visible for test purposes throughout the full length of the containers.

The invention is illustrated in the accompanying drawing, in which:

Figure 1 is a perspective view of the device, the parts being shown in operative positions.

Figure 2 is a vertical central section of the same.

Figure 3 is a side elevation, the parts of the apparatus being shown in inoperative positions in dotted lines.

The apparatus as constructed includes a casing comprising a block 1, preferably of wood or similar material, which is of the full sectional dimensions of the casing. The lower portion of the block is cut away, leaving a relatively thin rear wall 2 and providing a space 3 in advance of the rear wall. The casing is completed by a metallic strip 4 bent into U-form, with the side walls 5 secured to and coextensive with the vertical dimension of the block 1 and the bottom wall 6 underlying and forming a bottom for the space 3. The side walls 5 thus provide side walls for the space 3 below the upper solid portion of the block 1, so that the space 3 is open only toward the front.

The solid portion of the block 1 above the space 3 is formed with vertically ranging, preferably cylindrical bores 7, and secured to the bottom of the upper solid portion of the block is a plate 8 formed in line with the bores 7 with openings 9 which have a diameter somewhat less than that of the bores to provide a narrow annular ledge 10 at the bottom of the bores 7.

A mirror or other reflecting surface 11 is rotatably supported on a shaft 12 within the space 3, the shaft being approximately aligned with the axes of the bores 7 to thereby permit the mirror 11 to reflect light into the bores throughout a considerable variation in the angular position of such mirror. The ends of the shaft 12 are provided with finger grips 13 by which the shaft may be turned to adjust the angular relation of the mirror with respect to the bores 7.

An inverted U-shaped frame including side bars 14 and a cross-bar 15 is pivotally supported at the forward upper edge of the block 1, the free ends of the bars 14 being preferably mounted on suitable pivots and arranged between the surface of the block 1 and the side walls 5. Supported in the side bars 14 adjacent the cross-bar 15 is a shaft 16 having terminal finger grips 17 by which the shaft may be turned. A mirror or other reflecting element 18 is connected to or supported by the shaft 16.

The side walls 5 near the bottom wall 6 are formed with longitudinally extending channels 19 opening through the forward edge of the walls 5 and the relation of the parts is such that when the arms 14 are swung downwardly, the shaft 16 will enter the channels 19, thus carrying the mirror 18 within the space 3 below the mirror 11, as indicated by dotted lines in Figure 3.

The device is designed to be used in connection with test tube light containers 20 which are of glass throughout and which are designed to be passed more or less loosely longitudinally of the bores 7 with their lower closed ends resting upon the supporting ledge 10.

The materials to be tested are placed in one of the containers or tubes or in both, according to the nature of the test being carried out. Light from any appropriate source is controlled either from the mirror 11 or from the mirror 18 and either such reflecting surface is manually adjusted until the reflected light is sent directly through the materials in the tubes. The other mirror, either 11 or 18 as the case may be, is then manually adjusted until the light reflected to the eye is that moving axially of the containers or, in other words, until the containers are visible throughout their full lengths. The reflected light is thus directed throughout the full length of the tubes and from the receiving mirror to the eye of the observer in order that the requisite test of the contents of the tubes may be made.

The device is useful for many purposes. It will serve admirably as a colorimeter wherein a standard fluid is introduced into one of the tubes 20

and the fluid being tested introduced into the other of said tubes. Under the reflected light, any variation in color is readily perceived.

To illustrate in the determination of blood sugar 5 a known quantity of the protein free blood filtrate is treated with a reagent which produces a color, the intensity of which depends on the amount of sugar present.

This is placed in one of the tubes. A standard 10 solution of sugar similarly treated with the above reagent is introduced by means of a graduated pipette, burette or other device, until the colors in both tubes as reflected on the mirrors are of equal intensity. Knowing the strength of the 15 standard solution, the strength of the unknown is easily calculated.

This is more easily accomplished and with greater accuracy with this invention than with others as the reflected color images on the mirrors are more easily differentiated than by direct vision, since this method allows the use of both eyes and at such distance from the color image as is most suitable for the observer.

Where great accuracy is not essential this instrument 20 allows also of the use of direct observation and color comparison.

The device also serves for testing oils, colloids 25 and illuminating fluids to discover the character and gradation as well as amount of any carbon or other contained impurities and the character of such may, if desired, be compared with a standard fluid in the other container.

The device also lends itself admirably for the 30 testing of various materials incident to health tests and other uses.

The device as a whole is compact and when the 35 parts are in inoperative position, as illustrated in Figure 3, it will be apparent that the mirrors or other reflecting elements are completely housed and protected against damage.

What is claimed is:

1. A testing apparatus including a casing having 40 vertically arranged spaced bores, said bores terminating above the bottom of the casing, the lower portion of the casing presenting an enclosed area opening toward the front of the casing, a mirror swingingly mounted in said area, a U-shaped frame pivotally connected to the upper portion of the casing and movable into selected positions above the bores, and a swinging 45 mirror carried by said frame.

2. A testing apparatus including a casing having the upper portion thereof formed with longitudinally ranging spaced bores, a mirror swingingly mounted in the lower portion of the casing below the bores, arms pivotally connected to the upper portion of the casing and movable into a selected position above the bores, a mirror adjustably supported in said arms, the length of the arms permitting the mirror carried thereby to be moved into the space below the bores for housing 5 purposes.

3. A testing apparatus including a casing formed with longitudinally ranging spaced bores, said bores terminating above the lower end of the casing, a mirror swingingly mounted in the lower 10 end of the casing below the bores, arms pivotally connected to the casing and movable to a selected position above the bores, a mirror swingingly supported in said arms, the length of the arms permitting the mirror carried thereby to be moved 15 into the space below the bores and beneath the first mentioned mirror for housing purposes.

4. A testing apparatus including a casing formed with longitudinally ranging spaced bores, the lower portion of the casing below the bores 20 presenting an open space, a mirror swingingly mounted in said open space, arms pivotally connected to the upper portion of the casing, a shaft carried by the arms, and a mirror fixed to the shaft to permit mirror adjustment, the length of the arms permitting the mirror carried thereby to be moved into a position below the first mentioned mirror and housed in said space, the side 25 walls defining the space being slotted to receive the shaft.

5. A testing apparatus including a casing formed with vertically arranged spaced bores terminating above the lower end of the casing, a mirror adjustably mounted in the casing below 30 the bores for directing the reflected light longitudinally of the bores, and a second mirror connected to the casing for bodily movement and for independent swinging adjustment to permit 35 said second mirror to be arranged above the bores to render visible the full length of the bores under such reflected light, said second mirror being movable into a position adjacent the first mentioned mirror for housing purposes.
